PULL TAB

Herman R. Markert, Hartsville, S.C., assignor to Sonoco Products Company, Hartsville, S.C., a corporation of South Carolina

Filed Oct. 25, 1967, Ser. No. 9,160

Term of patent 14 years

(Cl. D9—256)

Fig. 1

Fig. 2

I claim:

The ornamental design for a pull tab, substantially as shown.
